Washington, D. C.

Application March 11, 1938, Serial No. 195,385

3 Claims. (Cl. 128—399)

Our invention relates to a device for treatment of inflammations, such as sinus inflammations.

An object of the invention is to provide a device for carrying cooling means for cooling definite areas on the head of the user.

A further object of the invention is to provide a harness member which is simple in construction, easily put in place, and will hold the cooling means in a definite fixed relationship during use.

10 Yet another object of the invention is to provide containers for cooling means which are efficient and easy to fill with cooling medium, will not leak, and which can be easily detached from the supporting harness.

15 With these and other objects in view, which may be incident to our improvements, the invention consists in the parts and combinations to be hereinafter set forth and claimed, with the understanding that the several necessary elements comprising our invention may be varied in construction, proportions and arrangements, without departing from the spirit and scope of the appended claims.

In order to make our invention more clearly understood, we have shown in the accompanying drawings means for carrying the same into practical effect without limiting the improvements in their useful applications to the particular constructions, which for the purpose of explanation, 20 have been made the subject of illustration.

In the drawings:

Figure 1 is a perspective view of a harness for supporting cooling means on the head of the user;

Fig. 2 is a perspective view of a container for 25 a cooling medium, with the top open;

Fig. 3 is a view similar to Figure 2, showing the container with the top partially closed;

Fig. 4 is a view similar to Figure 2, showing the container totally closed;

40 Fig. 5 is a view in front elevation of the same form of harness shown in Figure 1, with the containers in place;

Fig. 6 is a perspective view of another form of harness member;

45 Fig. 7 is a perspective view of yet another type of harness member for holding containers for cooling medium;

Fig. 8 is a detail front elevation of a form of container for cooling medium adapted to fit 50 over the nose;

Fig. 9 is a cross sectional view taken along the line 9—9 of Figure 8, looking in the direction of the arrows.

Referring to the drawings, we have shown a harness member comprising a headband 1 of

open or leno weave fabric so that the fabric will not insulate the cooling medium in the containers which are attached thereto. At the edges 2 and along the strengthened portions 3 the fabric is tightly woven to give it strength. Along the tightly woven portions 3 are located grommets 4, to which may be attached containers for cooling means. The headband 1 terminates in strengthened portions 5 to which are stitched at 6 elastic members 7 for holding the headband 1 tightly 10 on the head.

The strengthened portions 5 are strengthened by a double line of stitching at 8. Adapted to fit over the top of the head is a support band 9 having tightly woven edges 10 and strengthened 15 portions 11 which carry attaching grommets 12.

The back end of the support band 9 has a strengthened portion 13 reinforced by a double line of stitching 14. To the strengthened portion 13 are stitched elastic inserts 15 which are 20 also stitched at their lower ends to the strengthened portions 5 of the headband 1.

Adapted to be attached at the grommets 4 and 12 of the head harness are container elements 16. These container elements 16 are made of 25 molded rubber with attaching tabs 17 formed of the material from which the containers are made. Eyelets 18 are molded in the attaching tabs 17.

The molded rubber containers 16 are provided with foldable tops, indicated generally by the numeral 19, which are creased as indicated at 20 to permit the foldable top to fold in on itself on the lines of creasing, as indicated in Figure 3. One element 21 of a snap fastener is attached to the upper portion of the foldable top 19, which 30 cooperates with another element 22 of the snap fastener which is located near the bottom portion of the foldable top member. As indicated in Figure 4 when the snap fastener element 21 is attached to snap fastener element 22, the top 40 19 presents a tightly folded condition which makes the container 16 waterproof so that any ice cubes, or other cooling medium, which may be placed in the container 16, upon melting, will not discharge liquid on the outside of the container 16.

In use, the harness shown in Figure 1 is placed over the head of the user, as illustrated in Figure 5, and the containers 16, which may be filled with cooling medium such as an ice cube, are 50 held in place by means of cords 23 which are passed through the eyelets 18 in the holding tabs 17, and then through the grommets 4 shown in the head harness. As illustrated in Figure 5, one or more containers 16 can be attached to the 55

top of the head through the cords 23. Two containers 16 can be attached, if desired, on either side of the forehead above the eyes, though in Figure 5 but one such container is shown in 5 place, and other containers 16 can be suspended below the eyes of the sufferer. A tying cord 24 can be run through the lower holding tabs of the container 16 positioned below the eyes to hold these containers 16 tightly pressed against the 10 face over the sinus cavities located below the eyes of the user.

In Figure 6 we have shown a different type of harness which we have indicated generally by the numeral 50. This comprises a headband 51 and a support 52. The headband 51 is formed with apertures 53 located above the eyes of the user so that the containers will be directly in contact with the head of the user without the interposition of the fabric material from which the 20 headband is made. Likewise the support band 52 is provided with an aperture 54 for the same purpose.

In the form of device shown in Figure 6 the headband 51 is somewhat shorter than the headband 1 of the form shown in Figure 1. In Figure 25 6 the headband is shown tapered at its ends 55 and attached to elastic elements 56 which are attached to a holding strip 57 at the back. Also attached to this holding strip 57 are elastic members 58 which are attached to a holding strip 59 carried by side strips 60 formed on the supporting band 52.

In Figure 7 we have shown a spectacle type of holding member which comprises a spectacle frame 70 having ear members 71 which are adapted to fit over the ears, and a bridge member 72 which is adapted to fit over the nose of the user. Usual nose pads 73 are formed on the bridge piece 72, these nose pads 73 operating as 30 similar pads operate in the usual type of spectacle. In place of the usual lenses carried by spectacles, we have shown attaching means on the spectacle frame, as indicated at 74. These attaching means are formed by bending the wire 35 40 of the spectacle frame upon itself to form upper loops 75. The holding tabs are threaded on the spectacle frame from the ear pieces 71. The lower holding tabs of the containers 16 are threaded on to supports 76 formed at the lower 45 50 part of the attachment means 74. A support 77 is formed on each attaching means which fits under the lower wall of each of the containers 16.

Turning to the form of device shown in Figures 8 and 9, we have shown a moldable container, one 55 55 of whose walls is of a shape to fit the bridge of the nose of the user. This nose piece is indicated generally by the numeral 80. The wall is indicated by the numeral 81.

Please note that the wall 81 is formed with a 60 wall 82 which fits over the bridge of the nose of the user. Crushed ice 83, for instance, may be inserted in the nose piece, which is provided with the usual foldable top 84. Holding tabs 85 are formed at the top, and holding tabs 86 are formed 65 70 at the bottom. Through holding tabs 85 the device may be attached to the headband of the head harness, and a holding string 87 may be attached to the holding tabs 86 to hold the nose piece firmly against the face of the user.

70 While we have shown and described the preferred embodiment of our invention, we wish it to be understood that we do not confine ourselves to the precise details of construction herein set forth by way of illustration, as it is apparent that many changes and variations may

be made therein, by those skilled in the art, without departing from the spirit of the invention, or exceeding the scope of the appended claims.

We claim:

1. In a device for treating sinus infections and other inflammations of the head, a harness for supporting units, containing a cooling medium, in place against the areas to be treated on the head of a patient, comprising an open weave strip adapted to fit around the forehead and sides of the head of the user, said open weave strip being provided with tightly woven laterally extending borders and tightly woven transverse panels which intersect said tightly woven borders, an elastic band joining the free ends of the strip, a supporting strip of open weave joined to the middle of the first mentioned strip, said supporting strip being also provided with tightly woven borders and tightly woven intersecting transverse panels, elastic strips joining the other extremity of the said supporting strip to the first mentioned strip, said supporting strip being adapted to fit over the top of the wearer's head from the front towards the back, and means attached to both the first mentioned strip and the supporting strip at the points of intersection of the tightly woven portions to attach the said units to the said strips in such a manner that the units are separated from the head of the patient by the open weave portion of the harness. 20

2. In a device for treating sinus infections and other inflammations of the head, a harness for supporting units, containing a cooling medium, in place against the head, one of said units being positioned on the top of the head of the patient, one on each side of the forehead above the eyes, and one on each side of the nose below the eyes, said last mentioned containers being suspended from the containers positioned on the forehead by flexible means, comprising an open weave strip adapted to fit around the forehead and sides of the head of the user, said open weave strip being provided with tightly woven laterally extending borders and tightly woven transverse panels which intersect said tightly woven borders, an elastic band joining the free ends of the strip, a supporting strip of open weave joined to the middle of the first mentioned strip, said supporting strip being also provided with tightly woven borders and tightly woven intersecting transverse panels, elastic strips joining the other extremity of the said supporting strip to the first mentioned strip, said supporting strip being adapted to fit over the top of the wearer's head from the front towards the back, and means attached to both the first mentioned strip and the supporting strip at the points of intersection of the tightly woven portions to attach the said units to the said strips in such a manner that the units attached directly to the strips are separated from the head of the patient by the open weave portions of the harness. 40 50

3. In a device for treating sinus infections and other inflammations of the head, a harness for supporting units containing a cooling medium in place against the head, one of said units being positioned on the top of the head of the patient, one on each side of the forehead above the eyes, and one on each side of the nose below the eyes, said last mentioned containers being suspended from the containers positioned on the forehead by flexible means, comprising an open weave strip adapted to fit around the forehead and sides of the head of the user, said open weave strip be- 70 75 80 85 90 95 98

ing provided with tightly woven laterally extending borders and tightly woven transverse panels which intersect said tightly woven borders, an elastic band joining the free ends of the strip, a supporting strip of open weave joined at the middle of the first mentioned strip, said supporting strip being also provided with tightly woven borders and tightly woven intersecting transverse panels, elastic strips joining the other 5 extremity of the said supporting strip to the first mentioned strip, said supporting strip being adapted to fit over the top of the wearer's head from the front towards the back, and means attached to both the first mentioned strip and the

supporting strip at the points of intersection of the tightly woven portions to attach the said units to the said strips in such a manner that the units attached directly to the strips are separated from the head of the patient by the open weave portions of the harness, said units comprising a hollow, molded, rectangular shaped, rubber member having attachable tabs, a foldable top, and means attached to the top to secure it when in folded position to prevent leakage of the contents. 10
